UNITED STATES PATENT OFFICE.

RUBE A. DOLES, OF EDDYVILLE, KENTUCKY.

POLE FOR VENTILATING HAYSTACKS.

1,286,562.

Specification of Letters Patent.

Patented Dec. 3, 1918.

Application filed February 14, 1918. Serial No. 217,111.

To all whom it may concern:

Be it known that I, RUBE A. DOLES, a citizen of the United States, residing at Eddyville, in the county of Lyon and State of Kentucky, have invented certain new and useful Improvements in Poles for Ventilating Haystacks, of which the following is a specification.

My invention relates to new and useful improvements in a hay stack pole and more particularly to a pole for ventilating hay stacks.

The principal object of my invention is the construction of a pole in such a manner that the stack will be ventilated throughout its height and breadth.

Another object is the construction of the pole in such a manner as to allow for the settling of the stack.

20 A further object is the provision of transverse pipes which are detachably connected to the central vertical pole and vertically adjustable thereon.

Still another object is the construction of the pole in such a manner that it will drain the condensation from the stack.

With these and other objects in view, my invention consists in the novel details of construction and the arrangement of parts 30 which will be more fully understood from the following specification and drawings in which:

Figure 1 is a side elevation showing the stack broken away to show the pole.

35 Fig. 2 is a transverse section on the line 2—2 of Fig. 1 looking in the direction of the arrows.

Fig. 3 is a fragmental enlarged detail showing a section through the central pole 40 and one of the transverse pipes, and

Fig. 4 is a fragmental detail illustrating a slightly modified form of transverse pipe.

In the drawings the numeral 1 indicates a hollow pole which tapers from the bottom 45 toward the top and said pole is provided throughout its length with openings 2 the purpose of which will be presently described. Elongated vertically extending openings 3 are formed in the pole 1, the 50 openings on opposite sides of the pole registering as more particularly illustrated in Fig. 1 of the drawings. Any desired number of openings 3 may be made vertically of the pole and in Fig. 1 of the drawings I 55 have illustrated three sets of said openings. Pipes 4 having a plurality of perforations

5 therein are adapted to extend through the openings 3 as is more particularly illustrated in Fig. 1 of the drawings. These pipes 4 may be of any desired length and 60 the ends thereof are preferably left open.

I also provide ventilating pipes adapted to be adjustably and detachably connected to the central pole 1 whereby as many pipes, as desired, may be used for stacking the hay 65 to various heights or such pipes may be arranged at various intervals apart to be determined by the ventilation desired. These pipes are indicated at 6 and are provided with a plurality of perforations as indicated at 7. The pipes 6 are provided on one end with an extension 8 which in turn has a right angle extension 9 which extends across and is spaced from the end of the pipe as is more particularly illustrated in 70 Fig. 2 of the drawings. The right angle extension is provided with a projection 10 and the end of the pipe is beveled as indicated at 11 for the purpose as will be later described. The right angle extension 9 is 75 spaced from the end of the pipe 6 to such an extent as to allow the reception of the pole 1 as indicated in Figs. 2 and 3 of the drawings.

In Fig. 4 of the drawings I have indicated 80 a slightly modified form of pipe 6 which is forked on the end to form the spaced arms 12 adapted to extend on each side of the pole 1. These arms 12 are of such a length as to extend beyond the face of the pole 1 so that 90 when in position the stacked hay will rest upon said extended arms and hold the pipe in position.

It is well known that it is desirable to 95 ventilate a hay stack and it is for this reason that my invention is provided and I have constructed the same in such a manner that it may be used for stacking the hay to various heights and at the same time allow for the settling of the stack. The perforated pole 1 ventilates the stack throughout its height and the perforated pipes 4 and 6 ventilate the stack throughout its width. When in use the lower end of the pole 1 is embedded in the ground and the hay is stacked 100 therearound. At the desired intervals the pipes 4 are inserted, through the openings 3 in the pole 1, in such a manner that they will be at the upper ends of the openings. The said pipes 4 are of such a length as to 105 extend beyond the outer surface of the stack. When the stack settles the pipes 4

will be slid vertically of the openings 3. The detachable pipes 6 are connected to the pole 1 at the desired intervals by engaging the right angle extension 9 around the pole 5 as more particularly illustrated in Figs. 2 and 3 of the drawings. By providing the projection 10 on the right angle extension 9 it is necessary to slightly turn the pipe 6 when engaging it with the pole 1 or detach-
10 ing it therefrom. The beveled portion 11 cooperates with the projection 10 so that the pole may be passed through the opening. The pipes 6 will slide along the pole 1 as the stack settles.
15 When the modified form of pipe 6, illus-
trated in Fig. 4 of the drawings, is to be
used the arms 12 extend on either side of the
pole 1 and, as previously described, are of
such a length that the hay will rest upon
20 the ends of the arms for holding the pipes

in proper position and for adjusting them along the pole 1 as the stack settles.

Having fully described my invention, what I claim as new and desire to secure for Letters Patent is:—

25

1. A hay stack ventilator comprising a perforated pole having elongated openings therein, and perforated pipes extending through the elongated openings.

2. A hay stack ventilator comprising a 30 hollow perforated pole provided with vertically spaced elongated openings, and perforated pipes extending through the elongated openings transversely of the pole.

In testimony whereof I affix my signature 35 in presence of two witnesses.

RUBE A. DOLES.
